CLAIM

The ornamental design for a multi-compartmented
packaging container for ice cream or the like, as shown.

DESCRIPTION

FIG. 1 is a perspective view of a multi-compartmented
packaging container for ice cream or the like showing
my new design;

FIG. 2 is a side elevational view;

FIG. 3 is an end elevational view; and

FIG. 4 is an exploded perspective view thereof.

FIG.1

FIG.2

FIG.3

FIG.4
